ROUNDER HEAD BRACKET MOUNTING FOR SPINNING MACHINE

Henry J. McDermott, Collingdale, Pa., assignor to American Viscose Corporation, Philadelphia, Pa., a corporation of Delaware

Application November 29, 1954, Serial No. 471,727

1 Claim. (Cl. 18—8)

This invention relates to apparatus for spinning artificial threads and filaments and particularly to an improved mounting for the rounder which permits a great number of spinnerets to be located in a compact area.

The conventional spinning machine for synthetic filaments, such as viscose rayon and the like, comprises a rounder which is usually a stainless steel tube mounted in a bracket between contractable supports. The lateral space required for these rounder brackets or saddles is excessive and therefore prohibits the maximum number of rounders being located in a given distance on the spinning machine.

The present invention has for its primary object the provision of an improved device for mounting the rounder on the rail of the spinning machine so that the distance between centers of adjacent rounders can be reduced to not more than 1½ inches.

A further object of the invention is to provide a bracket attachable to the spinning machine rail having a rounder receiving socket on one side thereof and a thin plate for clamping the rounder head against said socket.

A further object of the invention is to provide, in a rounder bracket for spinning machines, a relatively thin resilient plate for clamping the rounder head against the bracket and means for securing the plate which are spaced from the center of the bracket.

Further objects will be apparent from the specification and drawings in which:

Figure 1 is a transverse sectional view of a portion of a spinning machine, part of which is sectioned as seen at I—I of Figure 2;

Figure 2 is a front view partly sectioned showing the upper part of the apparatus of Figure 1; and

Figure 3 is a bottom view partly sectioned of the structure of Figure 2.

The invention comprises essentially the provision of relatively thin, bored mounting brackets for spinneret rounders which are bolted to the vertical mounting rail of the spinning machine. One face of each bracket is recessed to provide a fluid-tight socket into which the rounder head is clamped by means of a thin, resilient stainless steel plate. The mounting brackets are provided with ears at the top and bottom thereof which are thinner than the body of the bracket proper. The plates are clamped to these ears and the reduced thickness of the ears accommodates the heads of the clamping cap screws of the adjacent assembly. When a plurality of these brackets are placed side by side, the construction permits extremely close spacing, and this is particularly so since it is not necessary to remove the plates independently of the brackets. The present construction permits even closer spacing of the spinnerets by having two rows of brackets in staggered relation to each other.

Referring now more particularly to the drawings, Figure 1 shows a portion of a conventional spinning machine in which a mounting rail or frame member 10 is supported on the spinning machine over the spinning bath into which the rounders 12, 12 extend. The lower

2

tips of the rounders are provided with jets or spinnerets 14, 14 through which the filaments are extruded into the spinning tubes 15, 15 in accordance with customary practice. The upper extremities of the rounders have 5 enlarged heads 16, 16, the back faces of which are slightly convex, as shown in Figure 2, and the front faces preferably being stepped to provide a sealing portion of reduced diameter. Each of my improved mounting brackets 17 is secured to the rail 10 by means of bolts 10 or cap screws 18, 18 and is bored at 19 to provide a passage in communication with the viscose conduit 20. The rounder heads 16 are also bored internally to provide a passage 21 (Figures 2 and 3) which communicates with the bore of the rounders and with passage 15 19. Brackets 17, 17 are relatively thin and have ears 25, 25 formed at the top and bottom thereof. The rounder head is securely clamped in the recessed bracket against a gasket 26 by means of a thin, resilient plate 27 held in clamped position by means of cap screws 28, 28. If desired, the cap screws may be shouldered or a spacing bushing 29 may be used to limit and control the pressure applied against the rounder heads through the plates. The ears 25, 25 are substantially thinner than the main body portion of the brackets so that when 20 the brackets are closely positioned, as shown in Figure 2, the heads of bolts 28 clear the main body part of the adjacent bracket. In this manner the rounders can be securely positioned on the mounting rail in very close lateral spaced relation so that the distance between 25 centers is not greater than 1½ inches. The convex faces on the rounder heads serve several important functions. In the first place, this provides concentrated pressure contact between the plates 27 and the rounder heads to assist in aligning the rounder heads in the sockets 30 and to prevent leakage. Also, the convex shape of the rounder heads permits the resilient spring plates 27 to deflect in the event that shorter bushings 29, 29 are used. The pressure applied to the heads through the 35 resilient plates is important in preventing leakage and in acting as a pressure relief valve in the event of a plugged jet. When the proper bushings 29, 29 are used in conjunction with known bending strength characteristics of the plates, the rounder heads will be forced away from the sockets in the event that the pressure in 40 the line exceeds a predetermined amount. The ability to provide an effective relief valve without the use of long coil compression springs is an important feature of the invention. Furthermore, the provision of the bushings against which the plates are tightly drawn assures constant and uniform pressure throughout the spinning machine which is so calculated to permit the rounders to be pivoted upwardly out of the bath 11 without bending or distorting them.

In order to limit the downward pivoted position of the 45 rounders, I provide adjustable stops 30, 30 in the mounting rail which can be locked in any desired position by means of lock nuts 31, 31. This stop cooperates with a projecting arm or abutment 32 on the rounder head, as shown clearly in Figure 1, to control the normal 50 operative position of the rounders. Figure 2 illustrates the manner in which the actual spacing between the total number of rounders in the spinning machine can be reduced to approximately ¾ of an inch by locating a second row of brackets above the lower row so that the 55 upper rounders extend downwardly between the lower rounders.

It will thus be understood that I have provided an improved bracket for mounting a spinning machine rounder which is readily detachable from the spinning machine and which enables very close spacing of the rounders to be achieved. This in turn reduces cost,

increases production and saves substantial space on the spinning machines.

Having thus described my invention, I claim:

In an apparatus for spinning artificial filaments, a container for a liquid spinning solution, a rounder carrying a spinneret at one end and having a substantially circular head at its opposite end, a supporting structure positioned adjacent to said container, and a mounting bracket carried by said supporting structure and engaging with said rounder head, said mounting bracket including a bracket body, means for detachably securing said bracket body to said supporting structure, a pair of ears formed integrally with and in the plane of said bracket body, said ears extending in opposite directions from said bracket body, a circular socket formed in said bracket body for receiving a portion of said rounder head for pivotal movement, a fluid passage extending through said bracket body and rounder head, a unitary flexible pressure plate engaging with the face of said rounder head opposite said bracket body, and means connecting said pressure plate to said pair of ears for resiliently urging said rounder head snugly against said bracket body to prevent leakage therebetween yet allowing pivotal movement of said rounder to and from said container, said face of said rounder engaged by said pressure plate be-

ing of convex form to facilitate a concentration of the resilient force thereagainst and thus assist in aligning said rounder head within said socket.
